(57) **CLAIM**

The ornamental design for a beverage cooler with storage compartment, as shown and described.

DESCRIPTION

FIG. 1 is a top, front, right side perspective view of a beverage cooler with storage compartment;

FIG. 2 is a bottom, rear, left side perspective view of the beverage cooler with storage compartment;

FIG. 3 is a front plan view of the beverage cooler with storage compartment;

FIG. 4 is a rear plan view of the beverage cooler with storage compartment;

FIG. 5 is a left side plan view of the beverage cooler with storage compartment;

FIG. 6 is a right side plan view of the beverage cooler with storage compartment;

FIG. 7 is a top plan view of the beverage cooler with storage compartment;

FIG. 8 is a bottom plan view of the beverage cooler with storage compartment;

FIG. 9 is a top, front, right side perspective view of a beverage cooler with storage compartment opened;

FIG. 10 is a bottom, rear, left side perspective view of the beverage cooler with storage compartment opened; and,

FIG. 11 is a right side plan view of the beverage cooler with storage compartment opened.

The broken lines and the areas encompassed by broken lines represent portions of the beverage cooler with storage compartment that form no part of the claimed design.
